COUNTER-BALANCED TELESCOPIC SUPPORT
Aldo Nasletti, 1540 Aguero St., Buenos Aires, Argentina
Filed June 21, 1963, Ser. No. 289,615
12 Claims. (Cl. 248—162)

This invention relates to a counter-balanced telescopic supporting arrangement for tables and the like and more particularly it refers to a telescopic column-like member, one end portion of which usually rests on the floor, either directly or through suitable legs, for instance of the tripod type, while the other end portion is provided with a supporting member, such as the board of a table, the seat of a chair and the like.

The arrangement is so counter-balanced that the adjustment of the height of the supporting member may be manually performed, without the operator having to exert a substantial pressure, taking into account the weight which is supported by the supporting member.

In a preferred embodiment, when a height decreasing adjustment is to be performed, the additional force required is minimum, while a height increasing adjustment may be carried out without additional force. Even when the weight is removed from the supporting member and the clamping means which maintains the telescopic arrangement in any predetermined position is opened, the expansion of the telescopic arrangement towards its maximum height position is gradually reached, without any bounce or similar sudden movement.

One of the preferred uses of the present invention is for tables for television sets, in which event an additional advantage is that the arrangement is so conceived that it may be rotated about its longitudinal axis. Most of the tables and frames for television sets, as nowadays manufactured, are not gradable in height and those which are, usually require that the television set is removed for carrying out any height adjustment.

Tables with supporting members defined by the board, which are rotatable about the vertical axis are known, but they all have an extra bearing and stub-shaft arrangement for that purpose while the present invention provides this additional feature without requiring further mechanical means.

Since television sets are of rather delicate nature, to provide a height gradable table which may be smoothly adjusted in height, without having to remove the television set therefrom and without requiring substantial forces, particularly when lowering the table with regard to the floor, are an aim since long ago.

The present invention resides therefore in a counter-balanced telescopic supporting arrangement for tables and the like, comprising a first pair of telescopic tubular members and a second pair of telescopic tubular members. The first pair preferably includes preloaded resilient means urging the first pair of telescopic members apart. The second pair of telescopic tubular members preferably includes load compensating means adapted to substantially counter-balance the preloaded resilient means. The first and second pairs of telescopic members being interrelated and one of the pairs of telescopic members including blocking means for blocking the arrangement at any desired height.

In order to facilitate the comprehension of the present

2

invention, reference will now be made to preferred embodiments in relationship to the accompanying drawings, wherein:

FIG. 1 is a perspective view, partially in section, of a counter-balanced telescopic supporting arrangement, according to the present invention.

FIG. 2 is a longitudinal section of the embodiment shown in FIG. 1.

FIG. 3 is a perspective view of a portion of the arrangement, showing in detail the clamping means.

FIG. 4 is a longitudinal section, in larger scale, of the lower end portion of both pairs of telescopic tubular members and accessories.

FIG. 5 is a longitudinal section, in larger scale, of the upper end portion of the inner tubular member of the inner pair of telescopic tubular members.

FIG. 6 is a longitudinal section, in larger scale, showing the upper end portion of the arrangement.

FIG. 7 is a side elevation of the plunger.

FIGS. 7A and 7B are side elevations of alternative embodiments of the plunger.

FIG. 8 is a bottom plan view of the plunger as seen along lines VIII—VIII of FIG. 7.

FIG. 9 is a top plan view of the plunger as seen along lines IX—IX of FIG. 7.

FIG. 10 is a schematic illustration of another embodiment.

As may be seen in FIGS. 1 and 2, wherein a first and preferred embodiment is shown, the latter is designed as a table for a television set and comprises a supporting member consisting of a board 11 for a television set (not shown). The board 11 is supported by a counter-balanced telescopic supporting arrangement 13 having a bracket 14 (see also FIG. 3) defining a plate 15 integral with a bushing 16 having recesses 17 in which the upper end of legs 18 (only one shown in FIG. 3) are mounted, which legs support the entire arrangement.

The counter-balanced telescopic supporting arrangement 13 comprises a first pair of telescopic tubular members, also called for this embodiment outer pair of telescopic tubular members, consisting of an outer lower tubular member 19 and a telescopically fit upper inner tubular member 20 (FIGS. 1 and 2). Thus the first or outer pair of telescopic tubular members are identified by reference numerals 19, 20.

The counter-balanced telescopic supporting arrangement 13 comprises a second pair of telescopic tubular members also called for this embodiment inner pair of telescopic tubular members, consisting of an outer upper tubular member 21 and a telescopically fit lower inner tubular member 22. Thus, the second or inner pair of telescopic tubular members are identified by reference numerals 21, 22.

Bushing 16 of bracket 14 comprises in its lower portion a shoulder 23 (FIG. 2) against which butts the upper end of the outer lower tubular member 19 which is fit into the bushing 16 by embossing a flange portion thereof through each of the perforations 24 (see also FIG. 3) within the recessed portion 17. The shoulder 23 is of larger cross-section than the width of the wall of the outer lower tubular member, 19, as is clearly shown in FIG. 2 so that the inner portion of shoulder 23 defines a circular inner abutment for the lower outwardly embossed end portion 20' of the telescopically fit inner

tubular member 20 which, when in its maximum distended position, enters in abutting contact with said circular inner abutment of shoulder 23 to avoid the telescopically fit upper inner tubular member 20 may be expelled out of the outer lower tubular member 19. The outer diameter of the lower outwardly embossed end portion 20' is slightly smaller than the inner diameter of the outer lower tubular member 19 and obviously likewise the outer diameter of the telescopically fit upper inner tubular member 20 is smaller than the inner diameter of the outer lower tubular member 19, so that the telescopically fit upper inner tubular member 20 may smoothly move within the outer lower tubular member 19.

To provide a good guidance between the telescopically fit upper inner tubular member 20 and the outer lower tubular member 19, the tubular member 20 is guided and retainable in any position by a clamping device 25, through which the tubular member 20 may slide. Thus, in any position of the telescopically fit upper inner tubular member 20 with regard to the outer lower tubular member 19, tubular member 20 is guided by the lower outwardly embossed end portion 20' and the clamping device 25.

Bracket 14 is a one-piece casted member including the bushing 16 and clamping device 25. The clamping device 25 is partially separated from plate 15 by a horizontal cut 26 which almost reaches the rear post 25A which is integral with plate 15. The rear post 25A is integral with a pair of substantially semicircular jaws 25B, 25B' ending in a pair of clamping tongues 25C, 25C' projecting in diametrically opposite direction with regard to rear post 25A. Jaws 25B, 25B' and clamping tongues 25C, 25C' are spaced apart from plate 15. A clamping screw 27 is rigidly and stationarily mounted by means of blocking pin 28 in clamping tongue 25C'. Clamping screw 27 projects through clamping tongue 25C and a manually operable pressure member 29 is screwed on the outwardly projecting portion on clamping screw 27. A resilient split expansion ring 30 is housed within the clamping device 25 and tends to resiliently space apart clamping tongues 25C, 25C'. Thus, by operating the manually operable pressure member 29, clamping tongue 25C will be either pushed towards or away from clamping tongue 25C', thereby respectively clamping or unclamping the telescopically fit upper inner tubular member 20 whereby, as will be later better seen, the height of board 11 with regard to bracket 14 may be changed.

The upper end portion of tubular member 20 (FIGS. 1, 2 and 6) is open and a spider supporting member 31 is preferably pressure fit on the outer face thereof. Spiders 31' support the board 11. A retainer pin 32 passes through the upper end portion of tubular member 20 and is mounted in the spider supporting member 31, and the purpose of which will be later explained.

The lower end portion of the outer lower tubular member 19 (FIGS. 1, 2 and 4) is inwardly bent, defining a base rim 19' for linking means 33 of the lower end portion 22' of the telescopically fit lower inner tubular member 22 to be supported by the base rim 19'. The lower end portion 22', similarly as base rim 19', is inwardly bent and penetrates into a gasket 34, preferably made of rubber, through which a large head anchoring screw 35 passes, the head 35' of which butts against the upper surface of gasket 34. A nut 36 including an upwardly projecting central guide member 36' is screwed on the large head anchoring screw 35 and presses the gasket 34 against head 35' at the same time as it supports a first washer 37 which has two functions. It presses the inwardly embossed neck portion 22' in sealing relationship into gasket 34 and since it is of larger diameter than the diameter of the telescopically fit lower inner tubular member 22, it provides an abutting surface for a helical spring 38, coiled around the telescopically fit lower inner tubular member 22 and to which reference will be made later on.

A second washer 39 surrounds nut 36 and is of larger

diameter than the first washer 37 and retained in place by counter-nut 40 of larger diameter than nut 36. It is apparent from FIG. 4 that the width of second washer 39 is substantially equal to the height of upwardly projecting central guide member 36' and that the width of the second washer 39 is substantially equal to the height of nut 36. The counter nut 40, besides of retaining the second washer 39, acts also as a counter-nut for nut 36. The diameter of the second washer 39 is such that the outer portion thereof rests on base rim 19'.

The upper end portion of the telescopically fit lower inner tubular member 22 (FIG. 5) comprises a sealing consisting of a seal member 41, usually made of neoprene having a central perforation and being housed between a pair of washers 42, 43. The sealing 41, 42, 43 is press-fitted between the embossed neck portion 44 and the embossed lid portion 45 of the telescopically fit lower inner tubular member 22.

The lower inner tubular member 22, as already stated, forms part of the second or inner pair of telescopic tubular members 22, 21 and the upper portion of tubular member 22 is slidably housed in the lower portion of the outer upper tubular member 21, the lower end of which is open at its end. The upper end of tubular member 21 (FIG. 6) is permanently linked to the foot 46' of a washer head 46 means of an inwardly embossed neck portion 21' entering in a pertinent annular recess, in said foot 46'. The upper portion of the washer head 46 is of larger diameter than said foot 46' and defines by its lower face an abutment for the upper edge of the outer upper tubular member 21 as well as an abutment platform for the pertinent end of helical spring 38, the other end of which rests on the first washer 37 (FIG. 4).

A central bore 47 defines in the upper portion of washer head 46 a nut seat, housing a nut 48 into which a stem 49 is screwed, the free end of which (FIGS. 2 and 7) supports a plunger 50. The plunger 50 consists of an upper small diameter washer 51 and a lower regular polygonal washer 52 which in this embodiment is an hexagonal washer, the diagonals of which are slightly smaller than the inner diameter of the lower inner tubular member 22 (FIG. 2) and are obviously considerably longer than the diameter of said washer 51. Between the upper small diameter washer 51 and the lower regular polygonal washer 52 (FIG. 7), a resilient plunger member 53 is fitted on stem 49 and having a circular cross-section the diameter of which is substantially equal to the inner diameter of the lower inner tubular member 22, but having at least one and in the embodiment shown, two bleeding sections defined in this embodiment by cut-off portions 53', 53'' (FIGS. 8 and 9) which are preferably slightly sloped from the lower base towards the upper base of resilient plunger member 53, as best shown in FIG. 7 at the cut-off portion 53''.

A fluid 54 (FIG. 2) is housed within the second or inner pair of telescopic tubular members 21, 22 and it can already be appreciated that when board 11 is moved toward bracket 14, that the resilient plunger member 53 will flex upwardly, as shown in dotted lines in FIG. 7, due to the fact that the upper washer 51 has a small diameter in comparison with the resilient plunger member 53, thereby facilitating the downward movement of board 11; while if a movement in opposite direction is performed, the lower regular polygonal washer 52, due to its larger cross sectional will maintain resilient plunger member 53 in the full line position, as shown in FIG. 7, thereby acting as a break against the expansion force of helical spring 38, which tends to move board 11 upward with a very fast movement, as soon as clamping device 25 is open, as will be later better understood.

If desired the resilient plunger member 53A (FIG. 7A) may be of circular cross section of substantially the same diameter as the inner diameter of tubular member 22, in which event, preferably, a bleeding bore 159 passes therethrough.

If the diameter of the plunger member 153 (FIG. 7B) is somewhat smaller than that of the lower inner tubular member 22, a bleeding passage is defined between the inner wall of the tubular member 22 and the periphery of plunger member 153. In that event the upper small diameter washer 151 is slidably arranged on the smaller diameter stub pin portion 149' of stem 149, so that when fluid pressure is exerted on washer 151 in downward direction as indicated by arrows 160, washer 151 tends to slide towards the lower stationarily mounted washer 152 which may be circular in cross section, and the resilient plunger member 153 is radially expanded, as indicated by arrows 161, thereby decreasing the bleeding passage and increasing the counter-balance. Since helical spring 38 is preloaded, even in the maximum distended position of the counter-balanced telescoping supporting arrangement, i.e.:

When the lower outwardly embossed end portion 20' is in abutting contact with shoulder 23, helical spring 38 always urges washer head 46 into contact with retainer pin 32 (FIG. 6), whereby the purpose of retainer pin 32, previously described, is now apparent.

The preload of helical spring 38 is such, that it tends to move board 11 upwardly, upon clamping device 25 being opened, with a force which is slightly larger than the weight which board 11 has to support, bearing in mind the breaking effect which provides the plunger 50 with its bleeding arrangement 53', 53".

On the other hand, if board 11 is to be lowered towards bracket 14, only a slight force will be required to be exerted on board 11 in addition to the weight which is supported by board 11, since the breaking effect of plunger 50 is substantially reduced in view of the flection of resilient plunger member 53 as described in connection with FIG. 7.

Conveniently, a rubber ring 55 (FIG. 2) is fit on the telescopically fit upper inner tubular member 20 and in abutting contact with the lower end of the spider supporting member 31, so that upon lowering board 11 to the maximum telescoped or collapsed position, said rubber ring 55 will cushion the impact on the upper surface of clamping device 25.

It will be apparent that the clamping device 25 may clamp and retain tubular member 20 in any desired position within the two maximum limit positions and that likewise the board 11 with the tubular member 20 may be rotated about the longitudinal axis of the arrangement, as soon as the clamping device 25 is unclamped.

As to the way of assembling the arrangement, in first instance the nut 48 is unscrewed from stem 49 and the stem 49 with the plunger 50 is inserted through the lower open end into the lower inner tubular member 22 and the upper end of stem 49 is passed through washer 42, seal member 41, washer 43. Thereafter, the head 35' of large headed anchoring screw 35 with the gasket 34 mounted thereon is fit into the lower end of tubular member 22 and thereafter the lower end portion 22' is embossed inwardly, as shown in FIG. 4.

At the same time the washer head 46 is fit into the upper end of outer upper tubular member 21. Thereafter, the tubular member 22 is partially inserted by its upper end portion into the lower end portion of outer upper tubular member 21 and the free end of stem 49 is passed through central bore 47, so that nut 48 may be screwed onto stem 49 and housed in the nut seat of bore 47.

Thereafter, helical spring 38 is slid onto the inner or second pair of telescopic tubular members 21, 22 until it abuts against washer head 46 and preloaded so that the first washer 37 with nut 36 may be screwed onto large headed anchoring screw 35 and maintain the assembly in preloaded condition. It is obvious that before fitting lower end portion 22' onto gasket 34, the fluid 54 has to be housed into the pair of telescopic tubular members 21, 22.

The inner or second pair of telescopic tubular members 21, 22 is then loosely housed in the telescopically fit upper inner tubular member 20 and the tubular member 20 by lower outwardly embossed end portion 20' is then inserted through the upper end of outer lower tubular member 19 until the second washer 39 abuts against base rim 19'. Thereafter, the bracket 14 is fit over the upper end of the telescopically fit upper inner tubular member 20 and inserted likewise over the upper end of outer lower tubular member 19 until shoulder 23 enters in abutting relationship with the outer lower tubular member 19. Thereafter, the upper portion of outer lower tubular member 19 is linked with the perforations 24 of bushing 16, as is already well known in the art.

Finally, the spider supporting member 31 with retainer pin 32 is pressure fit onto the upper end portion of the telescopically fit upper inner tubular member 20, whereby the entire arrangement is assembled and ready for use.

Although in this embodiment the second pair of telescopically tubular members 21 and 22 are housed within the first pair of telescopic tubular members 19, 20, it will be evident that this is not a fundamental requirement. In the embodiment shown in FIG. 10, the second pair of telescopic tubular members 121, 122 is arranged adjacent the first pair of telescopic tubular members 119, 120. Tubular member 121 is linked by arm 156 to tubular member 120 and likewise tubular member 122 is linked by arm 157 to tubular member 119. The upper end of tubular member 120 is provided with a spider supporting member 131 supporting a board 111, for instance of a table and the tubular member 119 is provided with a bracket 114 having at least one leg 118 in case the arrangement, as previously stated, forms part of a table which may for instance have four legs.

The second pair of telescopic members 121, 122 houses a hydraulic plunger arrangement of the type of plunger 50 described in connection with the first embodiment, while the first pair of telescopic tubular members 119, 120 houses a preloaded spring 158 of the type of spring 38.

Although two embodiments of the invention have been illustrated and described in detail, it is to be expressly understood that the invention is not limited thereto. Various changes can be made in the design and arrangement of the parts without departing from the spirit and scope of the invention as the same will now be understood by those skilled in the art.

I claim:

1. A counter-balanced telescopic supporting arrangement for tables and the like, comprising a first pair of telescopic tubular members and a second pair of telescopic tubular members, said first pair including preloaded resilient means urging said first pair of telescopic members apart, said second pair of telescopic tubular members including load compensating means adapted to substantially counter-balance said preloaded resilient means, said first and second pair of telescopic members being interrelated and one of said pair of telescopic members including blocking means.

2. A counter-balanced telescopic supporting arrangement for tables and the like, comprising an outer pair of telescopic tubular members and an inner pair of telescopic tubular members, said outer pair of telescopic tubular members having a first end and a second end, said inner pair of telescopic tubular members having a third end and a fourth end, said first end and said third end as well as said second end and said fourth end being linked together, a preloaded spring arranged between said inner and outer telescopic tubular member and in abutting relationship with said third and fourth end adapted to urge said pairs of telescopic tubular members apart, said inner pair of telescopic tubular members including load compensating means adapted to substantially counter-balance said preloaded spring, and manually operable

blocking means operable on one of the tubular members of said outer pair of telescopic tubular members.

3. The supporting arrangement as claimed in claim 2, wherein legs are connected to said blocking means for supporting the arrangement in spaced apart relationship from the floor and said first end being provided with a supporting member for a board.

4. A counter-balanced telescopic supporting arrangement for tables and the like, comprising an outer pair of telescopic tubular members and an inner pair of telescopic tubular members, said outer pair of telescopic tubular members having a first end and a second end, said inner pair of telescopic tubular members having a third end and a fourth end, said first end and said third end as well as said second end and said fourth end being linked together, a preloaded spring arranged between said inner and outer telescopic tubular members, and in abutting relationship with said third and fourth end to urge said pairs of telescopic tubular members apart, said inner pair of telescopic tubular members comprising a first tubular member defining said fourth end and having a perforated seal at its opposite end, telescopically arranged in a second tubular member defining said third end, a plunger slidably arranged in said first tubular member, a stem connected to said plunger and projecting through said seal of said first tubular member into said second tubular member and being rigidly connected to said third end, a fluid housed in said first tubular member, said plunger defining at least one bleeding passage, said fluid, plunger and bleeding passage being adapted to substantially counter-balance said preloaded spring, and manually operable blocking means operable on one of the tubular members of said outer pair of telescopic tubular members.

5. The supporting arrangement as claimed in claim 4, wherein said plunger comprises an upper small cross-sectional washer mounted on said stem, a lower larger cross sectional washer mounted on said stem, a resilient plunger member mounted between said upper and said lower washers, the cross-sectional area of said lower washer being as a maximum equal to the cross-sectional area of said resilient plunger member, said plunger member having at least one cut-off portion defining said bleeding passage, said resilient plunger member being adapted to flex towards said upper washer to increase the bleeding passage when moving in the direction of compression of said preloaded spring.

6. The supporting arrangement as claimed in claim 4, wherein said plunger comprises an upper small cross sectional washer mounted on said stem, a lower larger cross sectional washer mounted on said stem, a resilient plunger member mounted between said upper and said lower washers, said plunger member having at least one bore defining said bleeding passage, said resilient plunger member being adapted to flex towards said upper washer to increase the bleeding passage when moving in the direction of compression of said preloaded spring.

7. The supporting arrangement as claimed in claim 4, wherein said stem ends in a smaller diameter stub pin portion, an upper small cross sectional washer slidably mounted on said stub pin portion, a lower larger cross sectional washer stationarily mounted on said stub pin portion and spaced away from said upper small cross sectional washer a resilient radially expandable plunger member mounted between said upper and said lower washers, the diameter of said plunger member in uncomressed state, being smaller than the inner diameter of said first tubular member, said resilient plunger member being adapted to flex towards said upper washer to increase the bleeding passage when moving in the direction of compression of said preloaded spring.

8. A counter-balanced telescopic supporting arrangement for tables and the like, comprising a bracket defining a plate having two sides, a bushing integral with on one side of said plate and a clamping device integral with the other side, said clamping device, plate and bushing

defining a perforation, said bushing having a shoulder increasing the diameter of the lower portion of said perforation, an outer lower tubular member fit into said bushing and in abutting relationship with said shoulder, said shoulder having a larger cross-sectional area than the width of said outer lower tubular member, so that within said outer lower tubular member said shoulder defines an abutment, a telescopically fit upper inner tubular member partially slidably housed within said outer lower tubular member and projecting through said perforation of said bracket, said upper inner tubular member having a lower outwardly embossed end portion capable of entering in abutting relationship with said abutment of said shoulder, said clamping device being capable of blocking said upper inner tubular member in any position, said outer lower tubular member having a base rim, said upper inner tubular member having a free end portion, a spider supporting member fit on said free end portion, a retainer pin passing through said spider supporting member and said free end portion, said spider supporting member being adapted to support a board, a lower inner tubular member resting on said base rim and being sealed therefrom, said lower inner tubular member being housed in said outer lower tubular member and said outer upper tubular member, said lower inner tubular member being telescopically fit in said outer upper tubular member, said outer upper tubular member being housed in said upper inner tubular member, said outer upper tubular member having a free end, a washer head including a foot fit into said free end and in abutting relationship with said retainer pin, said washer head and foot being perforated and defining a nut seat, a nut in said nut seat, said telescopically fit lower inner tubular member having an upper end portion defining a perforated seal, a plunger slidably housed in said telescopically fit lower inner tubular member, a stem integral with said plunger and projecting through said last mentioned seal, said stem having a screw threaded free end passing through said perforated washer head and foot and screwed into said nut, a fluid housed in said telescopically fit lower inner tubular member, said plunger including a bleeding passage, a washer connected to said telescopically fit lower inner tubular member and resting on said base rim, a preloaded compression spring coiled around said outer upper tubular member and telescopically fit lower inner tubular member and abutting against said last mentioned washer and against said washer head thereby urging said tubular members apart.

9. The supporting arrangement as claimed in claim 8, wherein said bushing defining outside recesses, legs mounted in said outside recesses for supporting said arrangement in spaced apart relationship from the floor.

10. The supporting arrangement as claimed in claim 8, wherein said plunger comprises an upper small diameter washer mounted on said stem, a lower regular polygonal washer mounted on said stem, a resilient cylindrical plunger member mounted between said upper small diameter washer and said lower regular polygonal washer and in contact therewith the diagonal of said lower regular polygonal washer being substantially equal to the diameter of said resilient plunger member, said plunger member having at least one cut-off portion sloped from the lower regular polygonal washer towards said upper small diameter washer to define said bleeding passage, said resilient plunger member being adapted to flex towards said upper small diameter washer to increase the bleeding passage when moving in the direction of compression of said preloaded spring.

11. The supporting arrangement as claimed in claim 8, wherein a resilient ring is mounted on said telescopically fit upper inner tubular member and in abutting relationship with said spider supporting member.

12. The supporting arrangement as claimed in claim 8 wherein said clamping device, plate and bushing are an integral member, said clamping device comprising a rear

post, a pair of jaws integral with said rear post each ending into a clamping tongue, said clamping tongues and jaws being spaced apart from said plate and defining part of the height of said perforation, a resilient split expansion ring in said jaws urging said jaws and tongues apart, said telescopically fit upper inner tubular member being likewise slidably arranged within said part of said perforation defined by said resilient split expansion ring, a clamping screw passing through both of said clamping tongues, a blocking pin in one of said clamping tongues blocking said clamping screw against rotation and a manually operable pressure member screwed on said clamping screw and in abutting pressing contact with the other of said clamping tongues.
